UNITED STATES PATENT OFFICE.

ADOLPH R. WIENS, OF MILWAUKEE, WISCONSIN.

FEED MECHANISM FOR STRANDS.

1,084,773.

Specification of Letters Patent. Patented Jan. 20, 1914.

Application filed June 5, 1912. Serial No. 701,808.

To all whom it may concern:

Be it known that I, ADOLPH R. WIENS, a citizen of the United States, and resident of Milwaukee, in the county of Milwaukee and State of Wisconsin, have invented certain new and useful Improvements in Feed Mechanisms for Strands; and I do hereby declare that the following is a full, clear, and exact description thereof.

10 The primary object of my invention is to provide simple, positive and accurate means for feeding a predetermined number of strands of uniform length from a hopper to a position in alignment with a forming plunger, the strands being of any grade from the coarsest to the finest, their composition being metallic or fibrous.

Other objects of my invention are to provide means for centering the strands relative to length under the plunger incidental to said strands being formed or bent by the plunger; to provide means for agitating the strands whereby they are straightened out longitudinally in a single layer preparatory to being selected into predetermined desired groups for delivery to a receiver that is aligned with the plunger; to provide an automatically actuated disappearing stop-pin or pins for holding and releasing the layer 25 of strands incidental to a feeding operation; to provide a picker that operates in timed relation with the stop-pins whereby the selected group of strands is positively delivered to a receiver preparatory to their being 30 engaged by the forming plunger; to provide a delivery throat for the strands that communicates with a hopper the throat being adjustable as to gage, whereby single strands of different cross-sectional area may be admitted thereto after a predetermined set of 35 the throat-opening; to provide a forming sleeve for the strands through which the plunger is adapted to reciprocate.

With the above and other objects in view 40 the invention consists in certain peculiarities of construction and combination of parts as set forth hereinafter with reference to the accompanying drawings and subsequently claimed.

50 In the drawings Figure 1 represents a longitudinal sectional view of a feed mechanism embodying the features of my invention, the section being indicated by line 1—1 of Fig. 2; Fig. 2, a plan view of the same 55 partly in section as indicated by line 2—2 of Fig. 1, other parts being broken away

and in section below the plane of the indicated section to more clearly show certain structural features; Fig. 3, an enlarged detail sectional view showing the feed mechanism in the position it assumes in separating a layer of strands preparatory to the same being positively fed to the plunger; Fig. 4, a similar view illustrating the position that the picker and stop-pins assume when they 60 are aligned relative to the working or feed stroke of the picker; Fig. 5 illustrates the position of the stop-pins relative to the rearward or idle stroke of the picker; Fig. 6, a detail cross-section of the feed mechanism, 65 the section being indicated by line 6—6 of Fig. 5, and Fig. 7, a diagram view of a cam-controlled mechanism for longitudinally centering the strands with respect to the plunger.

70 Referring by characters to the drawings 75 1 represents a portion of a frame to which is secured a bed-plate 2, which bed-plate carries a forked throat-plate 3, the forked members of which throat-plate are provided 80 with strand-receiving recesses 4. Secured to the upper face of the throat-plate 3 is a forked roof-plate 5, which, in conjunction with the throat-plate 3 forms a throat recess that communicates with the receiver 4, 85 the throat being of an approximate width that is equal to the diameter of the largest strand that is to be operated upon. The throat-recess is preferably disposed upon an angle whereby strands may be delivered 90 thereto by gravity, the roof and throat-plate being forked for the purpose of forming a mouth through which forming mechanism is arranged to travel. The roof-plate has a vertically extended wall 6 that forms one 95 face of a hopper 7, the rear wall 6' of which hopper extends upwardly from the throat-plate 3. The end-walls of the hopper are formed by wings 8 that are slightly spaced from the side edges of the front and rear 100 walls of the hopper as best shown in Fig. 2, the said wings being adjustably secured to a squared rod 9, which rod is journaled in bearing-brackets 10 that extend from the frame 1, the rod being reciprocatively 105 mounted in said bearings. One end of the rod 9 carries a spanner 11 which is engaged by a stud 12 that projects from one end of a lever 13, the lever being fulcrumed to an ear 14 with which the frame is provided. 110 The opposite end of the lever carries a pin 15, which pin engages a cam groove 16 that

is formed in the hub of a gear-wheel 17, the same being loosely mounted upon a stud 18 that also extends from the frame 1.

Revolutely mounted upon the stud and secured to the gear-wheel 17 is a driving sprocket 19 and a driven smaller sprocket 20, the driving sprocket being arranged to receive power from a shaft through a link-belt, which mechanism forms no part of my invention and is therefore not shown. 6

10 Mounted in suitable journals that extend from the brackets 10 is a shaft 21, which shaft is driven by an endless chain-belt 22 that connects the sprocket-wheel 20 with a similar sprocket-wheel 20' that is secured to the shaft 21. The shaft 21 also carries a vibrating wheel 23 that is partially toothed about its circumference as best shown in Fig. 1, said vibrating wheel being alined centrally of the throat and arranged to actuate a tappet-shoe 23', which tappet-shoe is fulcrumed upon a pin between ears that extend from the lower face of the throat-plate 3. These ears as shown, form part of a bracket 24 that is rigidly secured to the lower face of the throat-plate, which bracket is provided with a well for the reception of a coiled spring 25. The coiled spring is arranged to engage the toe portion of the tappet shoe, which toe portion has a working face that is normally held by the spring just above the lower face of the throat, the heel of the shoe in which case is seated within one of the indentures of the vibrating wheel. 25

30 Thus it will be seen that when the vibrating wheel is rotated it will impart a vibratory motion to the tappet-shoe whereby the lower face of strands which are passing through the throat will be slightly agitated so as to cause said strands to straighten out longitudinally as they travel through the throat and be alined side by side in a parallel layer. 35

Secured to the lower face of the bed-plate 45 2 is a block 26 which is slotted for the reception of a retaining bolt 27 whereby the block is held, said block being adjusted longitudinally by a thumb-screw 28 that is in threaded connection therewith, the thumb-screw being loosely journaled in an ear that depends from the bed-plate. The forward end of the block has fulcrumed thereto a yoke 28, the front end of which carries a pair of stop-pins 29, which stop-pins are adapted 50 to move in and out of the line of the throat members of the throat-plate 3 and roof-plate 5. The stop-pins are normally held across the throat by means of a coiled spring 30, which is interposed between the block 26 and tail-piece 31 of the yoke. It will be observed that owing to the fact that the yoke which carries the stop-pins 29 is mounted upon the block, said stop pins can be adjusted longitudinally of the throat by 55 means of the adjusting thumb-screw 28. 60

Hence the position of the stop-pins with relation to the length of the throat can be changed whereby a greater or less number of strands can be fed during each operation, this adjustment of the feed being more fully 70 described hereinafter.

Suitably journaled in the frame 1 is a counter-shaft 32, which counter-shaft is driven by a gear-wheel 33 that is mounted upon said shaft and arranged to mesh with the gear-wheel 17 previously mentioned. 75 The counter-shaft carries an eccentric 34 upon which is mounted a strap 35 that has projecting therefrom a finger 36, the end of the finger being provided with a slot 36'. The finger is also provided with an intermediate guide-block 37, which guide-block is trunnioned in ears 38 that extend upwardly from the bed-plate 2. Hence it will be seen that when the counter-shaft is in motion the finger connections will cause the latter to reciprocate in approximate alinement with the throat and at the same time the end of said finger will oscillate vertically, the oscillation being sharply defined at the end of the reciprocative stroke due to the eccentric action imparted thereto co-acting with the sliding play of the finger through the trunnion block 37. The extreme end of the finger is provided with a depending picker 39, 80 which picker is arranged to enter the throat from the top and travel downwardly and thereafter recede from said throat and move upwardly to the position indicated in Fig. 1, in which position the finger has reached the 85 extreme end of its idle forward reciprocative stroke. 90

Secured to the lower end of a vertically reciprocative bar 40 is a forming sleeve 41, which sleeve is centrally alined relative to the feed throat being positioned between the forked ends of the throat-plate and roof-plate as best shown in Fig. 1. As indicated diagrammatically the reciprocative sleeve-carrying bar is in link connection with a 105 crank 42 that extends from a driven shaft 43 whereby vertical movement of the sleeve is had. This crank-shaft and connection forms no part of my invention and is therefore simply shown diagrammatically to 110 show means for reciprocating the forming sleeve. 115

Alined with the forming sleeve and adapted to co-act therewith is a forming plunger 44, which forming plunger is reciprocated in a similar manner to the sleeve but is arranged to have greater throw than the latter, the said plunger being, as shown diagrammatically, in link connection with a second crank 42' of the shaft 43, this crank 120 being of greater throw than the sleeve-operating crank, whereby the forming plunger is arranged to travel downwardly and through the forming sleeve, the said forming plunger being provided with a crotched 125 130

end for engagement with the nested group of strands which are delivered to the receiver.

To provide means for actuating the stop-pins 29 in timed relation with the picker 39 as shown in Fig. 1, the strap 35 from which the finger 36 projects is also provided with an extended toe 45, which toe engages the tail-piece 31 of the stop-pin carrying yoke 20 co-incident to entrance of the picker between the strands, whereby said stop-pins recede from the throat in order that the selected bunch of strands may be positively fed to the receiver.

15 In order to adjust the width of the throat which is formed between the roof-plate and throat-plate 5, 3, respectively, whereby said throat is gaged for maximum and minimum diameter strands, I provide a pair of shoes 20 46, which shoes are in dove-tailed engagement with recesses that are formed in the opposite side-walls of the roof-plate forks, the said shoes being held in this instance by set-screws 46' as best illustrated in Fig. 2. The 25 lower faces of the shoes serve to regulate the width of the throat passage whereby the desired gage of strand may pass therethrough, it being understood that said shoes may be interchangeable with similar shoes varying 30 in dimensions whereby the throat passage is more or less restricted or that a single set of shoes may be utilized for this purpose and adjusted to provide the necessary width of throat, in which instance suitable gage mechanism 35 not shown may be employed to indicate the position of adjustment relative to the gage of the strand that is to be fed.

It will be understood that this feed mechanism may be employed for various purposes 40 as, for example, in feeding tufts of bristles, fiber, or metal for the purpose of manufacturing brushes.

Assuming the working parts to be in the 45 position illustrated in Fig. 1, it will be observed that the picker is advanced forwardly of the stop-pins to a position in alinement between the fourth and fifth strands of a layer which is held in the throat by the stop-pins that are projecting across the throat-passage, it being understood that the strands are of uniform length. The next movement 50 of the eccentric 34 in the direction indicated by the arrow will cause the picker to enter the throat between said fourth and fifth strands, the point of the picker being projected below the upper face of the throat-plate. Incidental to this downward movement of the picker, the tongue 45 will engage the stop-pin yoke and cause said pins to recede from the throat, thus clearing the passage to the receiver 4. The picker will now move downwardly upon its working stroke while in its engaged position with the strands and will thus cause the four strands 55 forwardly thereof to be positively moved to-

ward the receiver co-incident to their travel. The strands back of the picker will now follow by gravity and in their flow will be agitated by the tappet-shoe through the engagement thereof with the toothed portion of the vibrator wheel 23, which agitating movement will thus loosen the strands and cause them to roll downwardly in the throat in a single layer. The tappet-shoe then comes to rest and the picker starts on its downward course and in its travel comes in alinement with the now depressed stop-pins, as shown in Fig. 4, the position of the eccentric 32 will be such as to cause the tongue 45 to disengage itself from the tail of the pin-carrying yoke, whereby said stop-pins will rise upward in alinement with the picker and upon opposite sides thereof. The stop-pins are now within the path of travel of the following strands and will thus prevent the same from further downward movement into the throat passage. Thereafter the picker will complete its downward or working stroke and will thus cause the four separate strands that are forward of the same to be delivered into the receiver 4. The forming plunger 44 will now move down and its crotched recess will engage the nested group of strands and cause the same to be bent midway of their length being forced by the plunger through the forming sleeve where the complete bending operation is effected, it being understood that the forming sleeve throughout a partial downward movement of the plunger follows the same to a predetermined position at which point it is momentarily held while the plunger passes through the forming sleeve and strips the now folded strands therefrom. Prior to the strands being delivered to the receiver the wings 8 which form the end-walls of the hopper are vibrated a predetermined number of times, whereby the ends of said strands are butted and alined, the configuration of the cam being such that when the vibration ceases, the last throw of the wings is just one-half of the complete throw, whereby the said strands are longitudinally alined centrally with relation to the plunger. This completes the operation of the feed mechanism and after the working stroke of the picker has been completed the same will rise clear of the throat passage and return to the position shown in Fig. 1 in advance of the stop finger. In connection with the operation of the plunger it should be understood that the latter travels through the slot 36 formed in the picker finger, said slot being of sufficient length to permit reciprocation thereof without interference with the movement of the plunger.

For clearness of illustration I have shown the feed mechanism adjusted for separating the strands into groups of four, but of course it is understood that the number of strands

may be varied indefinitely and that by adjusting block 26 which carries the stop-pin yoke, said stop-pins may be moved longitudinally with relation to the throat passage whereby the distance between the extreme point at which the picker enters the passage and said stop-pins may be varied, this distance determining the quantity or number of strands in a group. It is also apparent, after the strands have been properly deposited within the receiver that any suitable forming mechanism may be utilized for operating upon the same whereby they are bent into the desired shape whether a group of strands are fed at a time or a single strand is fed.

I claim:

1. A feed mechanism of the described character comprising a hopper having a restricted inclined throat through which strands are adapted to travel transversely, means for agitating the strands during their initial travel through the throat, cam-actuated wings for alining the strands longitudinally, a rotary eccentric, a strap mounted thereon, a finger extending from the strap, a picker carried by the finger arranged to enter and travel longitudinally of the throat passage, an oscillatory guide-block for the finger, a spring-controlled pivoted yoke, stop-pins carried by the yoke adapted to be moved across said throat passage, and means associated with the picker finger for actuating the stop-pin yoke in opposition to its spring-control.

2. A feed mechanism of the described character comprising a frame, an inclined throat-plate carried by the frame, a roof-plate disposed above the throat-plate, the roof-plate and throat-plate forming a restricted throat passage through which strands are adapted to travel, a hopper in communication with the throat passage, a spring-controlled tappet-shoe located in the throat passage, wings constituting end-walls of the hopper, means for vibrating the wings whereby strands passing through the throat passage are longitudinally centered, a strand receiving recess in the throat-plate, a reciprocative plunger alined with the recess and disposed centrally with relation to the length of the strands, a forming sleeve into which the plunger is adapted to enter, a bed-plate carried by the frame, an adjustable block in connection with the bed-plate, a spring-controlled yoke pivoted to the block, stop-pins carried by the yoke adapted to travel across the throat passage, a revoluble eccentric, a strap mounted thereon, a tongue extending from the strap for engagement with the stop-pin yoke, a finger extending from the strap, a guide for the forward end

of the finger, and a picker depending from the finger adapted to enter the throat passage and travel longitudinally thereof.

3. A feed mechanism of the character described comprising a hopper having a restricted inclined discharge throat through which strands are adapted to travel in a single layer, a receiver in connection with the throat, a horizontally reciprocative picker adapted to enter the throat at a predetermined point for feeding the strands in groups, a reciprocative stop-pin adapted to move into the throat at a fixed point for controlling the number of strands in the group fed, and means for causing the stop-pin to recede co-incident to movement of the picker upon its feed stroke.

4. A feed mechanism of the described character, a hopper having a discharge throat through which strands are adapted to travel, a vibrator adapted to engage the strands incidental to their travel through the throat, reciprocative means for alining the strands longitudinally incidental to their travel through said throat, a reciprocative picker, actuating means for causing the picker to enter the throat at the start of its feed stroke and thereafter travel longitudinally of the throat to effect a feeding movement, a stop-pin movable in and out of the throat at a fixed point intermediate of the stroke of the picker, and means for causing the stop-pin to recede from the throat co-incident to start of the picker upon its feed movement.

5. A feed mechanism of the described character comprising a hopper having a restricted inclined throat through which strands are adapted to travel transversely, means for agitating the strands during their initial travel through the throat, cam-actuated wings for alining the strands longitudinally, a rotary eccentric, a picker in operative relation with the eccentric, the picker being adapted to enter the throat and travel longitudinally thereof to effect a feeding operation, a guide-block for controlling vertical movement of the picker, a vertically reciprocative stop-pin adapted to move across said throat passage, and means for causing the stop-pin to recede from the throat passage co-incident to a feed movement of the picker.

In testimony that I claim the foregoing I have hereunto set my hand at Milwaukee in the county of Milwaukee and State of Wisconsin in the presence of two witnesses.

ADOLPH R. WIENS.
